ARTICULATE FIGURE

Frank Larned Treuting, Newark, N. J., assignor to
Herbert R. Treuting, Sr., Newark, N. J.

Application August 14, 1946, Serial No. 690,479

4 Claims. (Cl. 46—161)

1

This invention relates to an educational and amusement device and relates more particularly to an articulate figure.

It is well known that great interest is displayed by children and adults in figures such for example, as animals, birds, etc. It is well known that most children find considerable interest in most all animal toys and especially toys of this character in which the parts may be moved to adjust the figure to various postures, such as assumed in standing, jumping, sitting, etc.

Articulate toys have been made in many forms and constructions, but whereas movable members have been provided, the desired naturalness and characteristics of the object have been lost by reason of the mechanical structure necessary to make the figure adjustable. Furthermore, a device of the present type must not only retain the proportions and effectiveness of the figure portrayed, but must lend itself to manufacturing requirements for high speed production without sacrificing the contours or outline formations which serve to bring about a realistic effect.

It is therefore an object of the present invention to provide an articulate toy wherein the movable members thereof may be adjusted.

Another object of the invention is to provide an articulate figure having jointed sections capable of adjustment and having means for retaining the sections in adjusted relation.

Another object of the invention is to provide an articulate figure having the movable portions so constructed and arranged as to meet practical production requirements.

Another object of the invention is to provide a figure in which the body portion and movable parts attached thereto are so formed as to facilitate assembly in producing the complete articulate figure.

Other objects and advantages will be apparent from the following description together with the accompanying drawing, in which

Fig. 1 is an elevational view of an articulate figure constructed in accordance with the present invention;

Fig. 2 is a front end view of Fig. 1;

Fig. 3 is a rear end view of Fig. 1;

Fig. 4 is a longitudinal cross-sectional view of Fig. 1;

Fig. 5 is an enlarged transverse cross-sectional view taken on line V—V in Fig. 1, and

Fig. 6 is a top view of Fig. 1.

An articulate figure constructed in accordance with my invention may be in the form of any type of animal, as for example a horse. As shown

2

in the drawing the figure consists of a body portion 10, a neck portion 11, and head portion 12. The head portion includes a main section 13 consisting of a fore-piece 14 having two spaced flanges 15 between which one end 16 of the neck portion 11 is pivotally received by a pintel or rivet 17. To complete the head portion a jaw-member 18 is pivotally secured between and to the flanges 15 by a rivet 19.

The body portion 10 of the figure is provided with a front slot 21 by reason of flanges 22 and the other end 20 of the neck portion is disposed between and pivotally attached to the flanges 22. As shown, however, these flanges are so arranged and proportioned as to provide bearing surfaces for the ends 23 of front leg members 24 of the figure. The ends 23 being pivotally attached to the flanges by rivets 25.

The body portion 10 is also provided with a rear slot 26 between flanges 27. This slot is so proportioned as to receive the upper ends 28 of rear leg members 29. The ends 28 being pivotally attached to opposite flanges 27 of slot 26 by rivets 31.

Each leg member consists of an upper section A, an intermediate section B and a foot section C (see Fig. 1). The leg members are jointed in like manner and a description of one will answer for all.

As shown more clearly in Figs. 2, 3 and 5 the upper section A and intermediate section B of each leg member is jointed by means of a rivet 32 passing through enlarged terminal pieces 33 which are secured in firm contact by rivet 32. The terminal pieces 33 provide enlarged frictional areas, the purpose of which will be later explained. The foot member C is in the form of a slotted block (see Figs. 4 and 5) having flanges 34 in which the lower ends of the intermediate leg members B are disposed and pivotally attached. It will be noted that each foot piece is provided with two relatively large surface areas to frictionally engage the ends of the intermediate leg members B the advantage of which will be explained.

As shown in the drawing the illustrated embodiment of the invention is a caricature of a horse but obviously any other form of figure may be employed.

A figure constructed in accordance with the present invention may be of any suitable material such as wood, metal or molded from any desirable plastic material and the mane 36 may be of bristles glued or otherwise secured in a groove

37 and the tail 39 may also be of bristle and secured in a recess 39.

As will be evident from the foregoing description the present invention provides a novel arrangement of parts so assembled and related as to produce not only an interesting and attractive figure from the ornamental standpoint, but capable of being adjusted to various positions as an educational or amusement device.

As will be evident the various parts of the figure are generally flat or plate-like. The slots provided to receive movable parts are so arranged and proportioned as to make possible relatively large surfaces held in firm contact by rivets as described. The rivets are upset to such degree as to permit free movement of the parts but at the same time maintain a firm pressure between the contacting surfaces.

With this novel arrangement of movable members, each movable part may be adjusted to a selected position and by reason of the frictional contact between the large area flanges it is possible to maintain any selected adjustment of the parts so that the figure may be generally handled without disturbing the selected arrangement of the adjusted members. Furthermore, it is possible by reason of the large area foot pieces and the particular contour and distribution of weight in the body, to so adjust the body, head, legs and foot members, that the figure may be made to stand on the two back feet alone or on the two front feet. A leg may be raised to a number of novel and interesting positions or two legs may be raised from the ground and the figure balanced on the remaining legs. As above pointed out these variations in adjustments are made possible by the provision of large contact surface joints which are so formed as to blend in with the novel contours of the figure. In other words, the mechanical features necessary to permit multiple adjustment of the parts have been utilized in the formation of the figure and advantage has been taken of the configuration of each movable member to bring about a pleasing and ornamental result.

Although a preferred embodiment of the invention is shown and described herein, it is to be understood that modifications may be made therein without departing from the spirit and scope of the appended claims.

What is claimed is:

1. An articulate animal figure comprising a body portion, a head having a neck portion and front and rear leg members, said body portion having a front cavity, ends of upper portions of said front leg members pivotally attached to and held in frictional engagement to the outer surfaces of opposite walls of said cavity, said neck portion having opposite surfaces of one end thereof disposed in frictional engagement with the inner surfaces of the opposite walls of said cavity and pivotally attached to said walls, said body portion having a rear cavity, upper portions of said rear leg members having ends thereof disposed in said rear cavity and pivotally held in frictional engagement with the inner surfaces of the walls of said rear cavity.

2. An articulate animal figure comprising a body portion, a head having a neck portion and front and rear leg members, said body portion having a front cavity, ends of upper portions of said front leg members pivotally attached to and held in frictional engagement to the outer surfaces of opposite walls of said cavity, said neck portion having opposite surfaces of one end there-

of disposed in frictional engagement with the inner surfaces of the opposite walls of said cavity and pivotally attached to said walls, said body portion having a rear cavity, upper portions of said rear leg members having ends thereof disposed in said rear cavity and pivotally held in frictional engagement with the inner surfaces of the walls of said rear cavity, each of the other ends of said upper portions of said front and rear leg members having a recessed bearing surface, said leg members having lower portions, the upper ends of said lower portions each having a bearing surface and means for holding said upper and lower leg portions in pivoted frictional relation to said bearing surfaces.

3. An articulate animal figure comprising a body portion, a head having a neck portion and front and rear leg members, said body portion having a front cavity, ends of upper portions of said front leg members pivotally attached to and held in frictional engagement to the outer surfaces of opposite walls of said cavity, said neck portion having opposite surfaces of one end thereof disposed in frictional engagement with the inner surfaces of the opposite walls of said cavity and pivotally attached to said walls, said body portion having a rear cavity, upper portions of said rear leg members having ends thereof disposed in said rear cavity and pivotally held in frictional engagement with the inner surfaces of the walls of said rear cavity, each of the other ends of said upper portions of said front and rear leg members having a recessed bearing surface, said leg members having lower portions, the upper ends of said lower portions each having a bearing surface and means for holding said upper and lower leg portions in pivoted frictional relation to said bearing surfaces and a foot member for each of said lower portions of said leg members, each of said foot members having a slot to receive an end of a leg member and means for pivotally securing said foot and leg members in frictional relation.

4. An articulate animal figure comprising a head portion, a neck portion, a body portion and front and rear leg members, said head portion having a slot, one end of said neck portion disposed in said slot and in frictional engagement with the inner surface thereof, means for pivotally attaching said end to the walls of said slot, said body portion having a front cavity and a rear cavity, the other end of said neck portion disposed in said front cavity, in frictional engagement with the inner surface thereof, means for pivotally attaching said other end in said front cavity, the upper ends of said front leg members pivotally attached to the walls of said front cavity and in frictional contact therewith, the upper ends of said rear leg members disposed in said rear cavity in frictional relation to the surface thereof, foot members, each of said foot members having a slot to receive an end of a leg member and means for pivotally attaching said foot members to said leg members in frictional relation.
